March 29 1808

John Johnson

Letters Patent Issued March 19, 1808.

The Schedule is referred to in these Letters Patent and making part of the same containing a description in the words of the said John Johnson himself of a Wheel to run under water.

This wheel requires no other or greater motion of the column of water which is impinging against the floats than the common current running current of air. The wheel is calculated to run at the bottom of the stream under one drift 40. It may be applied to all kinds of mills & machinery which are usually worked by the means of water. The wheel may be four, five, six, in diameter and from ten to forty feet, and upwards in length, however the length depends on the power required. The wheel revolves vertically. The water impinges against the floats from the shaft to the uppermost part of the wheel for the water runs on the uppermost part over the wheel. The shaft may be any given length (according to the power required and the velocity of the water) thirty feet will be sufficient in length for any common mill work and from ten to twelve inches in diameter. In a wheel of thirty feet in length there ought to be five sets of arms, and those in each set. The number of sets of arms depends upon the length of the wheel. The arms ought to be made as small as is consistent with their strength in order that they may expose as small as possible a surface to be acted upon by the water in the revolution of the wheel. As soon as the water comes to impinge against the floats which are fixed to the extremity of the arms by a hinge they turn edgeways and move in the air, in that position until the current again begins to act - on them. These must be immersed to the height of half the diameter of the wheel or else the wheel sinks half its diameter down with the bottom of the stream and extends the bottom of the dam as far as necessary and the necessary joins it to the bank. Thus the lower part of the wheel will revolve in eddy water. The float is as long as the shaft and in a wheel of four feet diameter they will be one foot broad. There is one shaft (common) which extends out on the bank & to the height the arms are to be fixed, connected with the wheel shaft by an universal joint. The floats of a thirty feet wheel are thirty feet long and two feet broad in a wheel of five feet diameter, which presents a surface for the water to impinge against of sixty square feet. This wheel may be applied to the raising water for the supply of Towns, Farms, &c situated on the banks of Rivers.
